UNITED STATES PATENT OFFICE

FRITZ HÖLSCHER, OF LENGERICH, GERMANY

MACHINE FOR MAKING SQUARE-BOTTOMED PAPER BAGS WITH STEPWISELY FED PAPER TUBES

Application filed November 27, 1931, Serial No. 577,623, and in Germany November 28, 1930.

This invention relates to machines for making square-bottomed paper bags, especially those without side folders or folded tucks, and with stepwisely fed paper tube.

5 In machines of this character up to now during the intervals in the feeding of the paper tube at the front end of the same the bottom square has been formed by the co-operation of a sheet metal gauge and a reciprocating finger, pushing the paper over the folding roller. By this reciprocating finger in machines operating with high speed frequently tearing of the paper has occurred, especially if sensitive material, such as that 10 15 20

one which is well known under the trade name "Cellophane", is used for making the paper bag.

It is the object of this invention to avoid this drawback and to create an arrangement 25 for preventing the danger of tearing the material, occurring with the high speed. According to the invention with this intention one single pair of grippers is used, which, during the intervals, is caused to move 30 in the direction of the axis of the paper tube so as to be introduced into the slightly opened end of the tube, and then to grip the edge of the upper layer in its middle whereupon it is caused to perform a swinging circular movement by which the gripped layer is pulled over the edge of the ruler. It has been found that on account of the slight tension in which 35 the paper is kept any tearing of it is avoided.

After this swinging movement the pair of grippers is then released and returned.

Swinging grippers are well known in the paper bag machine art, even these which 40 perform a reciprocating as well as a swinging movement. The invention consists in the creating of a machine in which the grippers are so arranged as to clutch the edge of a layer of the tube in its middle, and then to perform a swinging movement around the 45 front edge of the folding roller and the cross-

wise arranged diagonal of the bottom fold respectively.

A preferred constructional form of the invention has been shown in a somewhat diagrammatic form by the drawings accompanying the specification, and wherein:

Fig. 1 is a side elevation of the main parts of the machine;

Fig. 2 is a still somewhat more diagrammatic side elevation drawn on a larger scale, 55 and in which for simplicity's sake parts have been omitted;

Fig. 3 is a partial plan view showing the pair of grippers in the moment in which they have just engaged the front edge of the upper 60 layer of the paper tube;

Fig. 4 is a side view of the grippers in another operative position;

Fig. 5 is a plan view corresponding to Fig. 3 showing the moment in which the diamond 65 fold has just been formed by the grippers.

It may be mentioned that in the drawings for simplicity's sake such parts, which are not necessary for understanding the invention and which are known as to their action, 70 have not been shown.

F is the framework of the machine supporting the cooperating parts. 1 and 2 are feeding rolls for repeatedly and in a stepwise manner feeding the paper tube 3 in the direction of the arrow in Figs. 1 to 3. 4 is a stationary knife which cooperates with a reciprocating knife 5, the latter being periodically moved up and down by known means (not shown) after the paper has been pushed 75 forward for the length necessary for forming a paper bag beyond the cutting level of the knives 4, 5.

For simplicity's sake in the following the cooperating parts may be described in connection with the description of their cooperation:

The paper tube 3 formed at the righthand of Fig. 1 by known means is pulled forward 80 by the above mentioned feeding rolls 1 and 85

2, and in this forward movement it surrounds the sheet metal form or gauge 6, the shape of which has been shown in dotted lines in Fig. 3. The feeding rolls 1 and 2 are periodically driven from the continuously rotating main shaft M of the machine by means of a crank disc A with adjustable crank pins B and a rod C pivoted to a tooth-segment D supported at E in the framework of the machine, which, by means of the tooth-wheel G operates another tooth-wheel which has the same diameter as the feeding roll 2, and which is so arranged upon the shaft of this roll that it only drives the same if the crank A, B swings the segment D opposite to the direction of the clockhand in Fig. 1. During the swinging movement the paper tube 3 is fed, whereas the feeding rolls are kept stationary when the segment D is rotated in the direction of the clockhand.

The two feeding rolls 1 and 2 are geared together in such a way that they simultaneously rotate inversely. The roller 1 is supported by a lever 1' in such a way that it may be elastically pressed by its own weight or other well known means against the upper side or layer of the paper tube. This feeding device is well known.

After the described feeding device 1 and 2 has fed the paper tube for a length dependent on the adjustment of the pin B at the disc A and has come to a standstill, then the knife 5, which up to this moment was in a lifted position, is moved downward cutting off between itself and the under-knife 4 the fed length of the tube, whereupon the knife 5 is at once lifted again. Now the devices which are significant for the present invention become operative. These devices comprise pins 7 arranged below the front end of the paper tube close to the cutting device 4, 5 periodically moved up and down, and one pair of grippers forming tongs 8, which performs a reciprocating as well as a swinging or oscillating movement. These parts in their action are co-operating with the gauge 6 within the paper tube and a ruler 9 situated close to the upper side of the tube.

As soon as the knife 5 is lifted, the two pins arranged at both sides of the middle line or axis of the tube, as may be seen from Fig. 3, are lifted so as to meet the underside of the paper tube outside of the front edges 6a of the gauge 6 arranged at a right angle to each other as shown in Fig. 3. By this, the tube at its cut front edge is slightly opened as outlined in Fig. 3 so that its upper layer is lifted away from the gauge 6. By this, the said layer is brought into a position in which it may be gripped by the tongs or pair of grippers 8.

This pair of grippers is supported sidewise from the paper tube and the sheet metal gauge 6 by an arm 30, rotarily arranged upon

a shaft H supported by the framework F. A projection 29 of this arm 30 is connected by means of a link 26 to a double-armed lever 25 rotarily supported at 25' in the framework F and bearing at its end remote to the link 26 a roll being held in operative connection by any well known means (for instance by springs which are not shown) with a cam disc 28 rotated from the main shaft M by a gearing, which has been shown in Fig. 1 but which needs no further description. This cam disc 28 is so arranged that it brings, immediately after the operation of the knife 5, the lever 25 from the dotted position shown in Fig. 2 into the position shown in full lines in the said figure, so that the arm 30 with the pair of grippers 8 is moved for a short way from the left to that position in which it has been shown in Figs. 1 and 2; during this movement the grippers are held separated, so that they may embrace the lifted upper layer in its middle at the point 10. When this has been done the pins 7, which may be operated for instance by a cam mechanism (not shown) from the main shaft M, or which may be dependent on the driving means of the knife 5 in such a manner that they are only lifted when the knife 5 has been completely lifted, may be sunk again below the level in which the paper tube is fed.

Between the arms 20, 21 of the grippers a compression spring 22 is arranged in such a manner that it always tries to keep the ends closed. The said pair of grippers is rotarily supported upon a shaft 30' arranged at the upper end of the arm 30 and is in connection with a sprocket or chain-wheel 14 supported by the same shaft. A chain 15 connects this sprocket wheel with another sprocket wheel 16 rotarily supported by the shaft H, and an adjustable crank pin 16' of this wheel is engaged by a rod 19 provided with a roll 18 at its other end, which is constantly kept in contact with a cam disc 17 on the main shaft M. Here as well springs or the like secure the continuous contact between roll and cam disc 17. Means of this character are well known in the art.

The periodical reciprocation of the rod 19 caused by the cam disc 17 periodically oscillates the chain wheel 16 and 14. The parts are so dimensioned that the oscillation of the wheel 14, and therefore that of the pair of grippers 8, embraces an angle of about 180°. Approximately at the end of the oscillation in one or the other direction, the arms 21, 22 respectively, meet fixed but adjustable stoppins 23, 24 respectively, at a cross-piece 30'' of the arm 30, whereby the spring 22 is compressed and the grippers opened.

In Figs. 1 and 2 the moment has been shown in which the arm 21 of the pair of grippers has been introduced by the swinging movement into the opened end of the paper tube (see Fig. 3) just after it has left the pin 23,

so that the spring 22 has been able to shut the grippers. In this moment the axis of the pin 30' is in alignment with the front edge of the roll 9, the grippers now performing the 5 oscillation or swinging movement under influence of the chain drive 14, 16 driven by the cam 17 and the rod 19 now pull the upper layer of the tube to the right over the upper side of the ruler into the position according to 10 Fig. 5, so that the diamond fold is made. The point of the front edge caught by the pair of grippers has then reached the point 11 in Fig. 5. In this moment the arm 20 has impinged upon the stop 24 and has opened the 15 grippers again. At the same time the drive for the feeding rolls 1 and 2 becomes operative again and the front edge of the tube, now provided at its front end with the diamond fold is drawn forward to the left for 20 one paper bag length, which is then cut off by the cutting device 4, 5 as described above. The diamond fold is passed through a pair of rolls 12, 13 and delivered to a pair of conveying bands J (outlined by dotted lines), 25 passed over a number of guiding rolls K and driven in any well known way by the main shaft. These conveying bands deliver the cut off part to a gluing device L and folding device N, which do not form a part of the 30 present invention and which finish the forming of the square bottom.

The diamond fold when it has left the rolls 12, 13 is secured against opening by means of a reciprocating finger O arranged closely 35 to the operating table P of the machine and reciprocated from the segment D by means of a link R. At the time during which the knife 5 is operated, the lever 30 with the pair of grippers at its free end has been swung again 40 to the left by the cam 28 and the cam 17 has swung the pair of grippers around the pin 30', so that the grippers have returned again to their initial position, thus the described play can begin afresh.

45 Having thus described my invention, what I claim as new and desire to secure by Letters Patent of the United States is:—

A machine for making a paper bag with a square bottom comprising intermittently operated feeding rollers for advancing predetermined lengths of a paper tube, a cutting device including an intermittently operated knife and a stationary knife cooperating to cut an advance length of the tube, a stationary rule determining the cross diagonal of the diamond fold for the square bottom, a sheet metal gauge engageable in the tube and having inclined front edges merging at a point adjacent the cutting device, a pair of vertically reciprocable pins between the cutting device and gauge and periodically movable toward the tube to open the front edge thereof after each operation of the cutting device, a pivotally mounted lever, a pair of 65 grippers arranged in tong form rotatably

connected with the upper end of the lever, the grippers having their gripping ends bent toward the longitudinal axis of the tube for gripping the tube at its longitudinal axis, means for swinging the lever to move the gripping ends into and out of gripping position, means for swinging the gripping ends to and fro after being moved into gripping position, and means to release the gripping ends from gripping position after the initial part of the to and fro swinging movement.

FRITZ HÖLSCHER.
